UNITED STATES PATENT OFFICE.

JOHN W. ROBINSON, OF LOWELL, MASSACHUSETTS.

GARMENT HANGER.

Application filed May 7, 1927. Serial No. 189,684.

This invention relates to a garment hanger and has for its object to provide a simple, efficient and inexpensive garment hanger capable of being detachably secured to clothes-hooks of ordinary construction so as to project therefrom and so as to be secured in substantially fixed relation thereto.

The garment hanger in its preferred form is provided with a garment-supporting member from which a plurality of garments may be suspended in spaced relation, and said member has mounted on it, a member capable of being slipped over the clothes-hook, and has connected with it means which co-operates with the said member and with the hook to detachably and frictionally secure the garment-supporting member in its projected position in substantially fixed relation to the hook.

20 The garment-supporting member has provision for hanging thereon a plurality of ordinary garment hangers, as will be described.

These and other features of this invention will be pointed out in the claims at the end of this specification.

Fig. 1 represents in elevation and section a detachable garment-hanger embodying the invention, and showing the same in operative relation to a clothes-hook;

Fig. 2, a section on the line 2—2, Fig. 1, through the garment-supporting member;

Fig. 3, a detail of a modified form of garment-supporting member, and

35 Fig. 4, an elevation of a modified construction of the garment hanger.

Referring to the drawing 10 represents a clothes-hook of ordinary construction, such as now commonly used in closets in houses, and which is secured to a wall of the closet, which wall is represented by the line 12.

The clothes-hook 10 is usually provided with upper and lower arms 13, 14 of unequal length, upon which the clothes are usually hung. The number of garments which can be conveniently hung upon the clothes-hook 10 is limited, and the present invention has for its object to provide a hanger from which a plurality of garments can be suspended, so that the garments may be kept in proper condition and individually suspended in spaced relation, which hanger is capable of being detachably and frictionally secured to the clothes-hook 10.

In Fig. 1, one construction of hanger is illustrated, which consists of a thin metal tubular member 16 split longitudinally and reinforced by a wooden or other non-metallic core or rod 17, into which may be screwed 60 a plurality of hooks or eyes 18 which are spaced apart and from each of which a garment, not shown, is designed to be hung.

The garment-supporting member 16, 17 is detachably and frictionally secured to the 65 clothes-hook 10 so as to project outwardly therefrom, preferably in a substantially horizontal plane.

In the present instance a preferred construction is shown for this purpose, which 70 consists of a ring-like member 20 mounted on the member 16, 17 to slide thereon and capable of being engaged with the upper surface of the upper arm 13 of the hook 10, and a second ring-like member 21, which is passed 75 through a hole in the member 16, 17 near the inner end thereof and is capable of engaging the under surface of the lower arm 14 of the hook 10.

By reference to Fig. 1, it will be seen that 80 the weight of the garment-supporting member tends to move the ring 21 upwardly and the ring 20 downward, and thereby cause said rings to frictionally grip the hook 10 and retain the garment-supporting member in its 85 operative position, and this frictional grip is increased as the garments are hung upon the hooks or eyes 18.

The garment-supporting member 16, 17 is readily detachable from the hook 10, and is 90 especially adapted to be used by persons traveling, as it can be readily packed in a bag or trunk and applied to any standard form of hook.

It will thus be observed that the garment-supporting member is provided with a ring-like member 20 for engaging the upper surface of the arm 13 of the hook 10 and has connected with it means for engaging the hook 10 so as to co-operate with the ring-like 100 member 20 and detachably and frictionally secure the garment-supporting member in a substantially fixed relation to the hook in a position in which it projects from the hook.

In Fig. 3, the ring-like members 20, 21 which engage the hook 10 are shown as partially closed rings or hooks, and the members 18 from which the garments are hung are shown as rings slidable on the garment-supporting member.

In Fig. 4, the garment-supporting member is represented as made from a piece of wire bent at its center to form upper and lower arms 23, 24 which are secured together at 5 their inner ends by twisting the end of the upper arm 23 about the lower arm 24. The upper arm 23 has the ring-like member 20 mounted on it to slide thereon, and the lower arm 23 has the ring-like member 21 connected 10 with it.

From the above description it will be seen that I have provided a garment-supporting member from which a plurality of garments may be hung, which is capable of being applied to hooks of ordinary construction, and frictionally secured in fixed relation thereto, and readily detached therefrom when not in use by movement of the supporting member in the direction of its length away from the 15 hook with which it co-operates.

What is claimed is:

1. A detachable garment support adapted 20 for use in combination with a hook provided with upper and lower arms, said support comprising a rigid garment supporting member 25 adapted to project from said hook with its rear end located between said upper and lower arms, a ring-like member mounted on said rigid garment-supporting member to slide thereon and engage the upper surface 30 of the upper arm of said hook, and a second

ring-like member connected with the rear end of said rigid garment-supporting member and engaged with the under surface of the lower arm of said hook and co-operating with 35 said first-mentioned ring-like member to detachably and frictionally secure the garment-supporting member in its projected position in substantially fixed relation to said hook.

2. A detachable garment support adapted 40 for use in combination with a hook provided with upper and lower arms, said support comprising a rigid garment-supporting member adapted to project from said hook with its rear end located between said upper and 45 lower arms, a ring-like member mounted on said rigid garment-supporting member to slide thereon and engage the upper surface of the upper arm of said hook, and a device connected with the rear end of said rigid 50 garment-supporting member and depending therefrom to be engaged with the underside of the lower arm of said hook and co-operating with the ring-like member to detachably and frictionally secure the garment-supporting 55 member in its projected position in substantially fixed relation to said hook between the arms of the latter.

In testimony whereof I have signed my name to this specification.

JOHN W. ROBINSON.
